WITNESS:

W. S. Pettit
INVENTOR
BY Victor J. Evans
ATTORNEY

UNITED STATES PATENT OFFICE.

WADE SLIFER PELLIT, OF HAMMOND, INDIANA.

DOOR LATCH AND LOCK.

Application filed May 24, 1924. Serial No. 715,679.

To all whom it may concern:

Be it known that I, WADE S. PELLIT, a citizen of the United States, residing at Hammond, in the county of Lake and State 5 of Indiana, have invented new and useful Improvements in Door Latches and Locks, of which the following is a specification.

This invention relates to locks and latches and has for its object the provision of a 10 novel device of this character constituting a radical departure from the ordinary and well known type inasmuch as the latch bolt is carried by the jamb, the keeper and lock mechanism being carried by the door.

15 An important object is the provision of a device of this character which, on account of the above mentioned feature, may be applied to a door of any size, thickness or the like with the utmost ease and simplicity, 20 the arrangement being furthermore such that the lock possesses the great advantage of being harder to pick or force than the ordinary variety.

Another object is the provision of novel 25 means connected or associated with the handles for effecting a positive lock either by means of a key or other equivalent element.

An additional object is the provision of 30 a lock and latch which will be simple to manufacture, inexpensive, easy to install, positive in action, efficient and durable in service, and a general improvement in the art.

35 With the above and other objects and advantages in view, the invention consists in the combination and arrangement of parts to be hereinafter more fully described and claimed and illustrated in the accompanying 40 drawings in which:

Figure 1 is an edge view of a door bearing a lock or latch constructed in accordance with my invention.

Figure 2 is a side elevation thereof.

45 Figure 3 is a side elevation, mostly in section, showing the interior mechanism and also illustrating the latch bolt mounted on the jamb.

Figure 4 is a section on the line 4-4 of 50 Figure 2.

Figure 5 is a detail cross-section on the line 5-5 of Figure 4.

Figure 6 is an elevation of a fragment of

the door cut ready for mounting the lock thereon.

Figure 7 is a detail view similar to Figure 4, but showing a modification.

Figure 8 is a detail plan view of the handles and yoke carried thereby.

Referring more particularly to the drawings, the letter A represents a door jamb and B a swingable or hinged door cooperating therewith. Ordinarily lock keepers are carried by the jamb and the latch bolts or locking bolts by the door, but in carrying out my invention, I follow the reverse order, the latch bolt 10 being mounted within a housing 11 let into the jamb. The latch bolt is carried by a stem 12 encircled by a coil spring 13 which operates to urge the 70 bolt into extended position projecting into the door opening.

The lock device comprises a casing 14 adapted to be mounted on the door and it is necessary that the door be cut away, as 75 shown at 15, to provide a hole 16 for the accommodation of the lock or latch mechanism. The opposite sides of the lock casing are formed with, or carry, face plates 17 which overlap the cut away portions to 80 make a finished appearance. The edge of the casing has an opening 17^a for the reception of the bolt 10 to constitute a keeper. Pivoted at 18 within the casing 14 is a plate 19 formed with a cam projection 20 and 85 having an extension 19^a to fit within the opening 17^a for forcing the bolt 10 out to release the door. Normally, this keeper

swings gravitationally away from the latch bolt so that the bolt 10 will enter the opening and hold the door closed. Journalized through the opposite face plates and passing through the hole 16 is a tubular shaft 21 carrying an angular arm 22 terminating in a cam-like end 23 adapted to engage the free or upper end of the keeper 19 and the cam projection 20 thereon for forcing the same into engagement with the latch bolt for forcing the same outwardly to disengage the door and permit opening. In the present instance the arm 22 is carried by a hub 24 surrounding the shaft 21 and secured thereto as by the screw 25 illustrated. Connected with the arm 22 is a retractile coil spring 26 anchored to the casing 14 and operating to hold the arm 22 normally in its

uppermost position so that the plate 19 will be in its lower position out of obstructing relation to the latch bolt. Movement of the arm 22 is limited by means of a guide bracket 27.

Extending through and beyond the ends of the tubular shaft 21 is a spindle 28 which has its intermediate portion formed with cam notches or recesses 29 for a purpose to be described. Secured to or formed on each end of the tubular shaft 21 is a handle 30 having a bore 31 therein registering with the bore of the tubular shaft. Rotatable in this bore 31 is a barrel 32 having a key slot 33 and normally held against rotation by spring-pressed pins 34 slideable within sockets 35 in the handle and engaging pins 36 located within holes in the barrel. The ends of the spindles are formed with sockets 37 adapted to receive the end of the key 38 and it will be observed that the key has suitable wards 39 which will engage the pins 36 and force the spring-pressed pins back into the recess 35 so that the points of engagement of the pins 34 and 36 will coincide with the wall of the bore 31 and permit turning of the key 38 and rotation of the spindle.

Mounted within the tubular shaft 21 are leaf-springs 40 lying within the notches or recesses 29 and carrying opposed outwardly extending terminal pins 41 normally projecting into holes 42 in the tubular shaft 21 and adapted to be projected into holes 43 in one of a pair of stationary sleeves 44 projecting from opposite sides of the lock casing and forming bearings for the tubular shaft. The notches 29 are peculiar in shape so as to define angular or inclined surfaces 44^a which are engageable with the pins 41 and which exert a wedging action thereon for forcing them outwardly when the spindle 28 is turned by inserting and rotating either key.

Ordinarily, that is, when the keys are not inserted, both handles and the tubular shaft are rotatable with respect to the spindle and it therefore needs the insertion and manipulation of a key to lock the mechanism. When a key is inserted in either handle and turned, the spindle will be turned, whereupon the cam surfaces 44^a will force the pins 41 outwardly through the holes 43, thereby locking the tubular shaft 21 to the sleeve 44.

In Figures 7 and 8 I have illustrated a modification in which the key locking means is replaced by slideable latches 45 mounted against the inner sides of the face plates and having operating buttons 46 movable along slots 47. In this form there is a different type of spindle including a U-shaped yoke 48 having an extension 49 on its bight portion corresponding to the cam end 23 of the arm 22. On the ends of the arms of this yoke are spindles 50 rotatable within

sleeve 51 and carrying handles 52. On the spindles are fixed collars 53 having recesses 54 adapted to receive the ends of the latches 45 for locking the parts together so that the yoke 48 cannot be swung to operate the plate 19. On the inner sides of the face plates are leaf-springs 55 adapted to enter notches 56 in the latches 45 for holding them in either selected position.

From the foregoing description and a study of the drawings, it will be apparent that I have thus provided a very simply constructed and easily installed lock device which requires no particular skill in its mounting, especially as there is so little preliminary work to be done on the door and its jamb. The device has the great advantage of being very difficult to open or pick from the outside and the lock consequently operates as a protection against unauthorized entry in addition to its other advantageous features.

While I have shown and described the preferred embodiments of my invention it is of course to be understood that I reserve the right to make such changes in the form, construction and arrangement of parts as will not depart from the spirit of the invention or the scope of the subjoined claims.

I claim:

1. In a door lock and latch device, an outwardly spring-pressed latch bolt mounted in the door jamb, a casing mounted in the door and having a keeper opening, a pivoted plate within the casing adapted to be engaged against the latch bolt for forcing the latter out of said opening, a spindle extending through the door and casing, a hollow shaft rotatable on the spindle, an arm on the hollow shaft adapted to engage and swing the keeper into operative position, handles stationarily mounted on the hollow shaft, and key operated means within the handles for locking the hollow shaft against rotation.

2. In a door lock and latch device, an outwardly spring-pressed latch bolt mounted in the door jamb, a casing mounted in the door and having a keeper opening, a pivoted plate within the casing adapted to be engaged against the latch bolt and to close said opening, a spindle extending through the door and casing, a hollow shaft rotatable on the spindle, an arm on the hollow shaft adapted to engage and swing the plate into operative position holding the bolt out of said opening, handles mounted on the hollow shaft, and means for locking the handles against rotation, including barrels located within the handles, keys co-acting therewith and engageable with the ends of the spindle, stationary guide sleeves for the hollow shaft, and a locking device carried by the spindle and including pins projectable through the hollow shaft and stationary sleeves.

3. In a door lock and latch device, an outwardly spring pressed latch bolt mounted in the door jamb, a casing mounted in the door and having a keeper opening, a pivoted plate within the casing adapted to be engaged against the latch bolt for forcing the latter out of said opening, a spindle extending through the door and casing and projecting beyond both sides thereof, a hollow shaft rotatable on the spindle, an arm on the hollow shaft adapted to engage and swing the keeper into operative position, handles on the hollow shaft, the spindle being provided with radial shoulders and inclined surfaces leading thereto, and pins slidably mounted radially through said hollow shaft and co-acting with said shoulders. 15

In testimony whereof I affix my signature.

WADE SLIFER PETTIT.
